UNITED STATES PATENT OFFICE.

JOHN JOSEPH RAWLINGS, OF SOUTH KENSINGTON, LONDON, ENGLAND, ASSIGNOR
OF ONE-HALF TO THE RAWLPLUG COMPANY LIMITED, OF LONDON, ENGLAND.

TUBULAR FIBROUS WALL PLUG.

Application filed March 26, 1926, Serial No. 97,801, and in Great Britain March 28, 1925.

This invention relates to improvements in tubular fibrous wall plugs of the kind comprising a number of twisted fibrous strands laid side by side and weakly held together, and the said invention provides improvements whereby the insertion of a nail or screw in a plug placed in a hole in a wall, or the like, is facilitated.

Wall plugs of the type hereinabove referred to, in which the fibrous strands are held together by an adhesive or by weak binding strands of fibrous material, as is well known, are expanded by the nail or screw inserted therein and, in some cases, a difficulty is experienced in driving in the nail or screw owing to the gripping action exerted thereon, more particularly when the strands comprised in such plugs are united, or loaded, with adhesive substances, such as glue, bitumen, gum, resin, and the like, or a mixture of such adhesive substances, owing to the combined effects of the heat developed by friction and the pressure exerted in expanding the plug, increasing the tendency of the nail or screw to adhere to the interior wall of the plug. A purpose of this invention is to provide means for minimizing this gripping or sticking of the nail or screw to the plug into which it is being driven.

According to this invention a tubular wall plug is provided comprising a number of twisted fibrous strands laid side by side and weakly held together by an adhesive having a thin layer of lubricant such as graphite, steatite, grease or the like applied as a lining or coating on the interior wall only of the plug. In one convenient arrangement according to this invention, a strip of paper or of textile fabric is impregnated with graphite, steatite, grease, or other suitable lubricant, or a mixture of these substances, and is arranged as a lining within the plug.

In another arrangement, in accordance with this invention, the lubricating material in a powdery or pasty form is applied to the interior of the wall plug without employing a separate lining material to hold or support it.

The accompanying drawings illustrate how the said invention can be conveniently and advantageously carried into practice:

In this drawing:—

Figure 1 is a diagrammatic perspective

view of part of a wall plug made in accordance with this invention.

Figure 2 is a diagrammatic view of apparatus suitable for producing a wall plug as shown in Figure 1.

Figure 1 shows a wall plug comprising a number of twisted fibrous strands *a* laid side by side in tubular formation around a tube *b* of paper or textile fabric impregnated with a suitable lubricant, inserted in the plug during the manufacture of the same by winding, wrapping or feeding the strip on a mandrel employed to form the tubular wall plug, and the strands comprised in the plug can then be built up on the lubricated strip thus brought to a tubular form, by any of the known methods of manufacture employed to produce this type of plug, the strip being drawn off the mandrel as the strands are brought together thereon, as will be readily understood, thus providing a continuous lubricating lining within the tube formed by the strands. The continuous length of tubular material thus formed can be cut to convenient lengths to form wall plugs. Such wall plugs can be cut from a length of tubular material produced by apparatus, as shown in Figure 2 comprising a reel *c* from which a strip of paper or textile material *b* is fed on to a mandrel *d* around which it is wrapped by passing through a substantially conical guide tube *e*. The tube of paper or textile fabric thus formed, impregnated with lubricant, is led between the mandrel and a guide plate *f* to which the strands *a* of twisted fibrous material are led from spools *g*. In passing through the annular space between the aperture in the guide plate and the mandrel extending therein, the paper or like tube and the strands are consolidated in a tubular formation.

The mandrel *d*, as shown in Figure 2, can be made tubular so that pulverulent, pasty or liquid lubricant can be pumped or fed through the same into the interior of the tube formed by the strands *a* brought to the required formation as they pass between the guide plate and the mandrel before they pass off from the end of the latter.

By mounting the spools *g* on a rotary head the strands in the tube produced can be given a spiral arrangement instead of lying straight in the longitudinal direction of the tube.

If desired the tube can be first formed of strands *a* and then liquid or pulverulent lubricant can be poured through the same to coat the interior wall of the tube, the excess lubricant being drained or poured out of the tube.

A plug resulting from this method of manufacture is thereby provided with a lubricating lining which prevents undue friction between the nail or screw and the interior wall of the tubular plug when the nail or screw is driven therein, and provides a plug especially suitable for holding screws which may be required to be withdrawn and replaced in the same hole from time to time.

In use the improved wall plug provided with a lubricant lining operates in the same manner as the fibrous tubular wall plugs heretofore known, the wall plugs being expanded by the nail or screw driven therein so as to grip or clamp the nail or screw firmly in the hole in which the plug has been inserted. The layer of lubricant thus provided is sufficient to facilitate the driving of the screw or nail into the plug without diminishing the gripping effort exerted on the

screw or nail by the plug and does not weaken the adhesion between the plug and the wall of the hole in which it is inserted.

I claim:—

1. A tubular wall plug comprising a number of twisted fibrous strands laid side by side and an inner tubular lining of fibrous sheet material impregnated with a lubricant.
2. A tubular wall plug comprising a number of twisted fibrous strands laid side by side and an inner tubular lining of paper impregnated with a lubricant.
3. A tubular wall plug comprising a number of twisted fibrous strands laid side by side in contact, and held together in tubular formation by an adhesive cement and a lining of lubricant on the interior wall only of the tubular structure.
4. A tubular wall plug comprising a number of twisted fibrous strands laid side by side and weakly held together by an adhesive cement, a lubricant on the interior wall of said tubular formation of fibrous strands, and means for carrying said lubricant.

JOHN JOSEPH RAWLINGS.
